UNITED STATES PATENT OFFICE

123,190

DESIGN FOR A COLORIMETER HOUSING

William B. Petzold, Pittsfield, Mass., assignor to
General Electric Company, a corporation of
New York

Application August 27, 1940, Serial No. 94,646

Term of patent 14 years

To all whom it may concern:

Be it known that I, William B. Petzold, a citizen of the United States, residing at Pittsfield, in the county of Berkshire, Commonwealth of Massachusetts, have invented a new, original, and ornamental Design for a Colorimeter Housing, of which the following is a specification, reference being had to the accompanying drawing, forming a part thereof.

In said drawing,

Figure 1 is a view in perspective of a colorimeter housing, showing my new design.

Figure 2 is a rear view.

I claim:

The ornamental design for a colorimeter housing, as shown.

WILLIAM B. PETZOLD.
